UNITED STATES PATENT OFFICE.

JOHN WALDHEIM, OF ELIZABETH, NEW JERSEY, ASSIGNOR TO UNDERWOOD TYPE-
WRITER COMPANY, OF NEW YORK, N. Y., A CORPORATION OF DELAWARE.

TYPEWRITING-MACHINE.

1,350,398.

Specification of Letters Patent. Patented Aug. 24, 1920.

Application filed September 10, 1918. Serial No. 253,368.

To all whom it may concern:

Be it known that I, JOHN WALDHEIM, a citizen of the United States, residing in Elizabeth, in the county of Union and State 5 of New Jersey, have invented certain new and useful Improvements in Typewriting Machines, of which the following is a specification.

My invention relates to typewriting machines of the class wherein a plurality of separate and distinct printing mechanisms or devices are provided, any one of which may be operated by a single set of key levers and from a single key-board; so that a plurality 10 of fonts of type differing in style from one another, or fonts of type adapted for writing in two or more languages, are available for use in the same machine; the machine being capable of adjustment in such a way that any one of the printing 15 mechanisms may be used at will.

The object of my invention is to provide certain improvements in machines of this type, and wherein the printing devices are 20 unitary structures insertible into and removable from the machine as a whole and at a single operation, whereby the number of kinds or styles of fonts of type usable in a particular machine is unlimited; this invention being an improvement upon the typewriter disclosed in my co-pending application filed March 20, 1918, No. 223,489.

A plurality of printing devices, preferably in the form of type-sets, comprise each 25 a type-bar supporting segment carrying a plurality of pivotally supported type-bars, the said printing devices being supported in fixed relation to one another by a movable member supported from the frame of the 30 machine; said printing devices being readily detachable as a whole and as unitary structures from the movable member whereby they are supported, so that any one or all of them may be removed from the movable 35 member and other printing devices substituted therefor; thus providing for the use of any number of printing devices and any number of styles or kinds of fonts of type in a single machine.

50 The movable supporting member provides for the movement of any one of the printing devices, which may be supported by it at any given time, into a position such that it will typewrite properly upon a work-sheet

supported by a carriage carried by the machine, all the printing devices being adapted to print at one and the same point; and means are provided for locking the movable member in positions such that any one of the printing devices carried thereby will be 60 in proper position for typing upon the work-sheet.

The movable supporting member is preferably in the form of a bar movable in the direction of its length along suitable guides 65 carried by the frame of the machine; and the said bar carries brackets whereby the printing devices are supported, and the construction of which brackets is such that any printing device may be readily removed 70 from the machine and another substituted therefor. Said bar is also provided with a rib having notches or recesses spaced apart from one another and adapted to be engaged by a swinging locking pawl to thereby lock 75 the bar in positions such that the printing device selected for use will print properly upon the work-sheet; the end portions of said rib being higher than the middle portion and forming stops for limiting the normal movement of the bar. The locking pawl may, however, be swung into an extreme position in which it will clear the end portions of the rib, thus permitting a further movement of the bar in order to carry 80 the type-sets supported thereby beyond and free from the frame of the machine to thereby facilitate their removal from the supporting bar, and in order that the frame 85 may not interfere with the substitution of one printing device for another.

Each printing device preferably comprises an upper type-bar supporting segment whereby a plurality of type-bars are pivotally supported; a lower cross-bar 95 which serves as a support for a plurality of pivotally supported type-bar-operating members operatively connected one with each of said bars; and connecting side portions whereby said cross-bar and segment 100 are connected together, whereby a unitary type-set, removable in its entirety and as a single structure from the movable supporting bar, is provided; the side portions of the type-sets carrying means whereby they are 105 supported from the brackets carried by the bar in such a way as to be readily detachable therefrom.

A single set of key levers is provided for operating all of the printing devices with which a machine may be equipped or which may be used therewith, said key levers being provided with means whereby they may be operatively connected with any particular printing device selected for use. In the embodiment of my invention illustrated, the key levers are provided each with a connecting member pivotally connected therewith, and the free ends of the connecting members are provided with pins adapted to be moved into and out of engagement with slots formed in the type-bar-operating members of the type-sets; simultaneous movement being imparted to the said connecting members by a movable bail extending through slots provided in said members, whereby all the connecting members may be moved in unison. The means whereby the bail is operated is connected with the swinging locking pawl in such a way that said connecting members and the pawl are operated together, and by one and the same operating means, to thereby simultaneously disconnect the connecting members from a type-set and unlock the movable bar, whereby the type-sets are supported, thus leaving the bar and type-sets carried thereby disconnected from the key levers and unlocked from the frame of the machine, and free to be moved to bring another type-set into position for use.

A single escapement mechanism is provided, the same being supported from the main frame of the machine and operatively connected with the carriage thereof. Each type-set, however, is provided with an individual universal bar, and the single escapement mechanism is operated by the universal bar of the particular type-set in use at a given time; motion being transmitted from the universal bar to the dogs of the escapement mechanism through a reciprocating pivotally supported intermediate member adapted to be engaged by any one of said universal bars, and which in turn is in engagement with the dogs.

Suitable mechanism for supporting and advancing a ribbon, and for shifting a portion thereof in unison with the platen as the same is moved into its upper and lower-case positions, will also be provided; the ribbon mechanism comprising vertically shiftable ribbon-vibrating members carried one by each of the type-sets and adapted to move the ribbon into the path of a type as it approaches the platen, together with operating levers, one associated with and adapted to operate each ribbon-shifting member; the said last-mentioned levers being carried by the platen-shifting mechanism, and motion being communicated to them from the universal bar of the particular type-set in use at a given time through

the reciprocating intermediate member above referred to. The free forward ends of the operating levers for the ribbon-vibrating members are guided by guides carried by the type-sets, and move with the type-sets along a rod, whereby they are supported as one or another of the type-sets is moved into a position for use; each operating lever being thus always associated with its own type-set and operatively connected with the ribbon-vibrating member thereof, although only the lever and ribbon-shifting member associated with the type-set in use at a given time are then in actual operation; one only of said operating levers being connected with and operated by the said reciprocating intermediate member at the time in question.

In order to provide for the convenient and ready removal of the type-sets from the machine as unitary structures, the connections between the ribbon-shafting members carried by the type-sets, and the levers which operate the same and which are permanently associated with the machine, are made readily separable as the type-sets are removed, preferably by providing a slot at the free end of each operating lever into which a pin at the lower end of the ribbon-shifting members may enter. The type-sets as a whole are supported from the movable bar or other supporting member whereby they are carried by brackets carried by the bar and having slots adapted to receive pins carried by the side members of the type-sets, a suitable locking member or device being provided for locking each type-set to the supporting member to which it is secured and whereby it is carried.

Other features and advantages will hereinafter appear.

In the accompanying drawings,

Figure 1 is a view showing my improved typewriter upon a vertical, centrally located plane extending from the front to the rear thereof.

Fig. 2 is a view showing a detail of the ribbon-shifting mechanism.

Fig. 3 is a skeleton perspective view, showing the principal operative elements of my invention.

Fig. 4 is a view showing a locking member for securing a type-set to its supporting member.

Fig. 5 is a view illustrating the universal bar of a type-set, and the guiding mechanism therefor.

Fig. 6 is a fragmentary front elevation illustrating the relation of the removable type-sets to the main frame of the machine, and showing one normal position of the support therefor as well as an abnormal position assumed by the support when a type-set is to be removed from the machine.

Fig. 7 is a fragmentary view illustrating

features for positioning the movable type-set supporting bar and locking mechanism associated therewith.

Fig. 8 is a view illustrating the operation 5 of removing a type-set from the supporting member whereby it is supported.

Fig. 9 is a fragmentary view illustrating the operation of freeing the key-levers from a type-set, and unlocking the supporting bar 10 therefor, preparatory to moving to a different type-set.

Referring to the drawings, the reference numeral 10 designates a suitable frame whereby the various elements which form 15 my improved typewriting machine are supported in proper relation with one another, the same having upwardly-extending standards 11 at its rear end which serve as supports for a rear carriage rail 12 which supports the rear end of a traveling carriage 13, and for an oscillating rod 14 to which two arms 15 and two members 15^a, for shifting the platen 16 vertically into upper and lower-case positions, are secured; the said 20 platen being supported in a platen frame having end plates 17, and the front end of the carriage having a roller which runs along a front rail 18 carried by upwardly-extending standards 19 at the front portion of the 25 framework. The two arms 15 are located near the standards 11. A shift bar 20, along which runs a roller 21 operatively connected with the end plates 17, is supported at its ends by the members 15^a, which are located 30 some distance outside of said arms 15. The arms 15 may be operated by upwardly extending arms 22 at the rear ends of shift levers 23 pivotally supported from a cross-bar 24 located at the rear end of the frame 35 of the machine, and which shift levers are provided with shift keys 25 at their forward ends and located in the keyboard of the machine, two such levers being employed, one 40 engaging each of arms 15.

Supported by the frame of the machine and preferably located near the rear end thereof is a guide shown as comprising two guideways 26 spaced apart from one another and having each a V-shaped groove as best 45 shown in Fig. 1 of the drawings, and 27 designates a bar having correspondingly V-shaped grooves and which bar is movable between and longitudinally of the guides 26, suitable balls 28 being ordinarily interposed 50 between adjacent pairs of grooves in order to reduce friction, as will be appreciated. The bar 27 is provided with forwardly-extending arms 29 located one at each end thereof and having bearings at their free 55 ends, and 30 designates vertically-extending shafts supported in said bearings, and the upper ends of which carry ribbon spools 31 which support a ribbon 32. The lower ends of the shafts 30 are provided with beveled 60 gears 33 which mesh with beveled gears 34

upon a horizontally-arranged ribbon-feeding shaft 35, through which the vertical shafts 30 may be operated to thereby wind the ribbon from one spool to the other, it being understood that there is an arm 29 at each 70 end of the bar 27, Fig. 6, and that a spool shaft 30 is supported in bearings provided at the forward end of each arm, although only one of said arms is shown.

The longitudinally slidable bar 27 also 75 carries a plurality of pairs of supporting brackets 36 extending forwardly therefrom, as many of such pairs of brackets being provided as there are type-sets or equivalent printing devices to be supported from the 80 bar 27. In the embodiment of my invention illustrated, two printing devices in the form of type-sets are provided and which are designated as a whole by the reference numerals 37, Fig. 3, although more than two printing devices may be provided for should it be deemed necessary or desirable to do so, all of said devices being supported from the longitudinally movable bar 27 and movable 85 therewith, as will be appreciated. 90

The type-sets 37 each comprise a type-bar supporting segment 38 which carries a plurality of type-bars 39 pivotally supported in slots 40 formed therein, and two depending side portions 41, the lower ends of which are 95 connected with one another by a cross-bar 42, Fig. 3; said cross-bar 42 being provided with a plurality of slots 43 within which a plurality of type-bar operating levers 44 are supported, one such lever being operatively 100 connected with each type-bar 39 through a pin-and-slot connection 45 at the upper end of said lever, as best shown in Figs. 1 and 8 of the drawings.

The several type-sets 37 are each detachably connected with the sliding bar 27 through and by means of the pairs of brackets 36 above mentioned, to which end the brackets which form each pair are provided with slots 46, 47, and the end members 41 110 of the type-sets with pins 48 adapted to enter the lower slots 47 and the upper slot 46 of the bracket which supports the inner one of the side portions 41, Figs. 1 and 6. The outer end members of the type-sets are 115 provided each with a slidable spring-pressed locking member 49 having a beveled head 50 adapted to lie in a correspondingly-shaped recess provided at the inner end of the upper slots 46 of the brackets which support 120 the outer end members 41, as best shown in Figs. 4 and 6; whereby when a locking member 49 is forced inward the beveled head 50 thereof is moved out of the recess in which it normally lies, thus permitting the type-set 125 with which it is associated to be swung forward upon the lower pair of pins 48, as shown in Fig. 8, and removed from the supporting bar 27 and from the machine by lifting the pins 48 out of the slots 47. Any 130

type-set or all of them may be thus removed from the machine, and other type-sets differing as to the character or style of the type carried by them may then be substituted for the sets removed; or type-sets adapted to typewrite in a different language may be substituted for those removed; a single machine being capable of operating with any number of type-sets, as will be appreciated.

The bar 27 is steadied in its movements and binding between the same and the guides 26 in which it moves, due to the offset arrangement of the type-sets and ribbon-supporting mechanism, which are ordinarily located to one side of the vertical plane of the bar and guides, is reduced, by the use of brackets 51 carried by the said bar and extending below the lower guide 26, and carrying rollers 52 at their lower ends; which rollers move in contact with a stationary rod or guide 53 supported from the frame of the machine as the bar and the type-sets carried thereby are shifted relatively to the frame of the machine.

The reference numerals 54, see Fig. 7, designate two recesses or notches formed in a rib extending from the rear side of the bar 27 and spaced apart from one another, 30 the middle portion 55 of said rib being of lesser height than the end portions 56 thereof, the purpose of the said notches being to lock the bar 27 in whichever one of the extreme positions into which it may be moved; the location of said notches being such that when the bar is locked, as aforesaid, one or the other of the type-sets carried thereby will be in proper position for typing upon a work-sheet carried by the 40 platen 16. The locking of the bar 27 in position such that any one of the type-sets may be used may be accomplished by means of a pawl 57, Figs. 1, 7 and 9, movable into and out of the notches 54, said pawl being carried by a shaft 58, the ends of which are journaled in the frame of the machine. Secured to this shaft 58 is a depending arm 59, the lower end of which is pivotally connected with a link 60. The forward end of 50 this link 60 is pivotally connected with the lower end of a lever 61 pivotally mounted at 62 on the frame of the machine, and the upper end thereof extends into convenient position where it may be manipulated by the operative, so that as the upper end of said lever is swung backward on its pivotal support 62 motion will be communicated to the pawl 57 through the shaft 58, and the free end of said pawl will be moved out of whichever one of the recesses 54 it may then lie in, whereupon the bar 27 and type-sets carried thereby may be moved sidewise along the guides 26 and a different type-set brought into position for use.

In shifting from one to the other of the two type-sets, which at any given time may be supported and carried by the bar 27, the pawl 57 need be moved rearwardly only far enough to clear the lower middle portion 55 of the rib upon the rear of the bar 27, after which the pawl may be released and permitted to remain in contact with and slide along said portion as the bar continues its movement until it is arrested by the inner end of the portion 56 of said rib, 75 which serves as a stop against the pawl 57. When, however, it is desired to remove one of the type-sets carried by the bar, the pawl 57 is moved rearwardly to a greater extent, Fig. 9, and to an extent such that it will 80 clear the higher end portions 56 of said rib. This permits the bar 27 to be moved to a greater extent than it is normally moved, as shown in dotted lines in Fig. 6, and to an extent determined by a stop 56^a which operates with the pawl 57, so that the type-set to be removed will be clear of the forward upwardly-extending standards 19, whereupon the same may be released from the upper slots 46 in the brackets 36 and 90 swung forward and removed from the machine, as shown in Fig. 8, preparatory to substituting a different style of type-set for the one removed. When desired, recesses or notches 54 may also be provided in end portions 56 adjacent stops 56^a, so as to enable bar 27 to be locked in position while type-sets are being inserted and removed.

Located within the space 63 of the frame of the machine is the keyboard, the same 100 comprising a plurality of key-levers 64 having operating keys 65 at their forward free ends, and the rear ends of which are pivotally supported from the frame of the machine in the slotted bar 24 hereinbefore referred to; springs 66, one for each key-lever, being provided in order to keep the same in their normal uppermost positions, and the forward end of said key-levers may be guided in a slotted plate or any other convenient manner.

A single set of key-levers is provided for operating the type-bars of all the type-sets with which the machine is equipped, and means are provided for operatively connecting the set of key-levers with whichever one of the plurality of type-sets the operator may desire to use. The connecting means employed in the embodiment of my invention illustrated in the drawings comprises a plurality of intermediate operating links 68, one for each type-bar, the lower ends of said links being pivotally connected with the key-levers at 69, and the upper ends thereof being operatively and detachably connected with the type-bar operating levers 44; to which end the said levers are provided with forwardly-extending portions provided with

slots 70 into and out of which pins 71 carried by the connecting links 68 may be moved.

Movement is imparted to the intermediate connecting links 68 to move the pins 71 into and out of engagement with the slots 70 of the bell-crank levers 44 of the particular type-set to be used, by means of a rod or bail 72 which lies in slots 73 provided in the intermediate links; the said bail being movable to thereby simultaneously swing all the said links about their pivotal connections 69 and move the pins 71 into and out of engagement with the slots 70. This bail 72 is supported by an oscillating shaft 74 supported in bearings provided in the frame of the machine by means of upwardly-extending arms 75 located one at each end thereof, and the upper ends of which arms carry said bail. One of the arms 75 is provided with a forwardly-extending portion 76, see Figs. 1, 3 and 9, having a headed pin 77 at its free end; which pin extends into a cam slot 78 provided in the link 60 through which the locking mechanism for the bar 27 is operated. This slot 78 is of such a form as to produce a forward movement of the bail 72 as the link 60 is moved forward by means of the lever 61, which forward movement of the bail will swing the set of intermediate links 68 forwardly about their pivotal connections 69; from which it follows that as the lever 61 is swung upon its pivotal point 62, the pawl 57 will be moved out of one of the notches 54, and the pins 71 of the links 68 moved simultaneously out of the slots 70 of the type-bar operating levers 44, thus disconnecting the key-levers from the type-set which they have been connected with and freeing the bar 27, so that the same, together with the type-sets carried thereby, may be moved sidewise by a finger-piece 67 extending forwardly from the slide bar 27. This releasing movement disconnects the key-levers from the particular type just previously in use, and permits a new type-set to be moved into proper position for use, whereupon, and as the lever 61 returns to its original position, the pins 71 will be moved back into engagement with the slots 70 of the type-bar operating levers 44 of another type-set, and the pawl 57 will enter the second notch 54, thus locking the bar 27 in position such that the second type-set is in position for use.

Supported by the frame of the machine is a bracket 79 which serves as a support for an escapement mechanism, whereby the movement of the carriage 13 for letter-spacing is controlled, and also as a support for means whereby said escapement mechanism is operated by and from the type-set in use at a given time.

The escapement mechanism is illustrated

as of a common type used in the standard Underwood typewriter, and as comprising an escapement wheel 80 connected (by the usual one-way pawls, not shown) with a pinion 81 in engagement with a rack 82 carried by the carriage, the carriage being moved by a suitable spring drum, not shown, and the step-by-step movement thereof being controlled by a pair of dogs 83, 84, carried by a dog-rocker 85 also supported by the bracket 79.

The dog-rocker 85 is operated by an intermediate reciprocating operating member 86 having a bar 87 which engages the dog-rocker 85, and which member is supported by a link 88, the ends of which are pivotally connected therewith and with the bracket 79, and by spaced upwardly-extending arms 89 of a rocker 90 also supported from the said bracket; said rocker having a depending arm 91, the free end of which is slotted, as at 92, and moves in sliding engagement with a bail 93 carried at the free ends of arms 94 located at the ends of an oscillating ribbon-feeding shaft 95, Figs. 1 and 2, supported in ears 96 shown as depending from two or more of the type-set supporting brackets 36. It therefore follows that the ribbon-feeding shaft 95 partakes of the longitudinal movement with the bar 27, and that the said shaft is operated from and by the intermediate reciprocating member 86 through the rocker 90, arm 91, and slotted end 92 thereof; the sliding engagement between the slot 92 and the bail 93 providing a permanent operating connection through which oscillating movement is imparted to the ribbon-feed shaft 95. This ribbon-feed shaft carries pawls 97 which engage the toothed periphery of a ratchet wheel 98 carried by the ribbon shaft 35 hereinbefore referred to, whereby oscillatory motion imparted to the ribbon-feed shaft 95 is communicated to the shaft 35 and rotates the same to wind the ribbon 32 upon one or the other of the ribbon spools 31.

The machine may be provided with a space-bar carried by levers, the rear ends of which are pivotally supported in the cross-bar 24, which levers will be operatively connected with an upwardly-extending arm adapted to engage the arm 91 depending from the rocker 90, to thereby operate the escapement independently of the key-levers, the same as in my co-pending case hereinbefore referred to, although these elements are not shown in the drawings.

Suitable ribbon-vibrating mechanism is provided, the same being supported from the shift-rail 20, whereby the platen is shifted, so as to partake of the vertical movements of the platen as it is shifted into its upper and lower-case positions, the construction of which mechanism is as follows.

The reference numeral 99 designates two arms carried on the shift rail 20, and which arms serve as supports for the ends of a rod 100, which rod in turn carries two vibrating members in the form of bell-crank levers 101, one such lever being provided for each type-set, although one only of them is shown; which levers slide along the rod 100 as the bar 27 is moved to bring either type-set into position for use. The vertically-extending arms of these bell-crank levers 101 are provided each with a pin 102, either of which pins may be moved into engagement with a slot 103, provided in an upwardly-extending arm carried by the intermediate reciprocating member 86, through which motion is transmitted to the escapement mechanism, whereby movement will be transmitted to said levers by the said reciprocating member.

The forwardly-projecting arms of the ribbon-vibrating levers 101 are adapted to be detachably connected with and disconnected from the lower ends of two vertically-movable ribbon-vibrating members 104, one of said members being associated with each type-set and carried by the type-bar-supporting segments 38 thereof; and in order to provide a separable operating connection between the said levers and the vibrating members 104, the aforesaid are provided each with a slot 105, into which slots pins 106, carried at the lower ends of the ribbon-vibrating members 104, may be moved, as will be understood from Fig. 8; this detachable driving connection being provided in order that each type-set may be moved out of operative relation with the ribbon-vibrating lever 101 with which it is associated in removing the type-set from the machine.

It will be understood that the intermediate actuating member 86 is located at the middle of the machine, and that the ribbon-vibrator levers 101 are movable sidewise and relatively to said intermediate actuating member 86 when the slide bar 27 is moved to bring another type-set into effective relation with the keys. It will also be understood that an additional sidewise movement is given to the slide bar 27 when it is desired to detach one of the type-sets so that it may be replaced by another. When this additional movement is imparted to the slide bar 27, it will be seen that the ribbon vibrator lever 101, associated with the type-set being removed to its replacement position, is out of engagement with the intermediate actuating member 86 and to one side thereof. To prevent the ribbon-vibrator lever from swinging about the bar 100 at this time, or, in other words, to guard against the pin 102 from coming out of alignment with the slot 103, so as to ascertain proper reengagement therebetween, the ribbon-vibrating lever is

provided with a finger 101^a which rests 65 against the shift rail 20, Fig. 8.

The ribbon-vibrating levers 101 move vertically with the platen because of the fact that they are carried by the rod 100 which, as explained, is carried by the shift rail 20, 70 during the movement of which the ribbon-vibrating members 104 follow the platen, because of their connection with the levers 101; so that the ribbon is maintained in proper position relative to the platen as the 75 platen is shifted, and when the same is in both its upper and lower-case positions. When the platen is in either of these positions, the ribbon is moved up simultaneously with the movement of a type-bar toward the 80 platen, because of the engagement of a pin 102 in the slot 103 in the reciprocating intermediate member 86, which is operated by the type-set in use; the movement of said member serving to rock the ribbon-vibrating lever 85 101, associated with the type-set in use upon the rod 100, and thus shift the ribbon into the path of the type, when the platen is in either its upper or lower-case positions. The free forward end of each ribbon-vibrating 90 lever 101 is guided in its vertical movements by guides 107, carried one by each of the type-bar segments 38, which guides, because of their engagement with the levers 101, act to slide the latter along on the rod 100, 95 whereby they are supported, as the bar 27 is moved to bring a type-set into position for use, and serve also to steady the forward ends of the shifting levers and maintain them in proper relation with the ribbon-vibrating members 104 operated by them. The reference numeral 108 designates a universal bar, Figs. 1 and 5, one bar being provided for each of the type-sets, and the same being segmental in form and operating in 100 curved slots provided in the rear faces of the type-bar supporting segments 38. These universal bars are engaged by the type-bars and moved rearwardly as the type-bars approach the printing point, which movement 105 is transmitted to the intermediate member 86, to thereby operate the escapement mechanism; to which end each universal bar is provided with a cross-bar 109, located in line with and adapted to engage the free forward end of said intermediate member 101. Each universal bar is guided and maintained parallel in its movement by means of a rock-shaft 110, supported in lugs 111, extending from the rear face of the segment 38, and 115 which shaft carries two arms 112 located one at each end thereof, as best shown in Fig. 5, the lower ends of which arms are pivotally connected at 113 with ears carried by the universal bars. The rock-shaft 110 also carries an arm 114, extending at right angles to the arms 112, and the free end of which is 120 connected with a bell-crank lever 115, pivot-

125

ally supported in a bracket 116, carried by the type-segment. The arm 114 and the horizontally-extending arm of the bell-crank lever 115 (see Fig. 8) are connected with each other through a link 117, and the vertically-extending arm of the bell-crank lever 115 is pivotally connected with the cross-bar 109 of the universal bar, this last-mentioned pivotal connection being at a lower level than the pivot connection between the lower ends of the arms 112 and the lugs with which they are connected. It therefore follows that as the universal bar moves rearwardly, it is maintained parallel with itself in all positions, because of the bell-crank lever 115 and arms 112 and 114, which, in effect, provide two bell-crank levers, the shorter arms of which are connected together through the link 117, while their longer arms are connected at points spaced apart from one another with the universal bar.

Variations may be resorted to within the scope of the invention, and portions of the improvements may be used without others.

Having thus described my invention, I claim:

1. In a typewriting machine, in combination, a set of key-levers, a plurality of type-sets, means for permitting a relative movement between each type-set and said set of key-levers, so as to bring any selected type-set and the set of key-levers into position to coöperate with each other, and means whereby said key-levers may be connected with or disconnected from the selected type-set while the latter is in coöperative relation therewith.

2. In a typewriter of the class described, a suitable frame; a set of key-levers supported by said frame; a supporting member carried by and movable relatively to said frame; a plurality of type-sets carried by said supporting member and each of which comprises a plurality of pivotally supported type-bars; means for locking said supporting member in positions such that each one of said type-sets will print at one and the same point; a plurality of connecting members pivotally connected one with each of said key-levers; means for moving the free ends of said connecting members into and out of operative relation with the particular one of said type-sets selected for use; and means for supporting a work-sheet in position such that it may be typed upon by any one of said type-sets.

3. In a typewriter of the class described, a suitable frame; a guide carried by said frame; a set of key-levers supported by said frame; a bar movable along and guided in its movements by said guide; a plurality of type-sets carried by and detachably secured to said bar; means for locking said bar in positions such that the corresponding type-sets will be effective, one at a time, to

print; and means whereby said set of key-levers may be operatively connected with and disconnected from the particular one of said type-sets selected for use, while the selected type-set is in effective position.

4. In a typewriter of the class described, a suitable frame; a guide carried by said frame; a set of key-levers supported by said frame; a bar movable along and guided in its movements by said guide; a plurality of type-sets carried by said bar; means for locking said bar in positions such that each one of said type-sets will print at one and the same point; a plurality of connected members pivotally connected one with each of said key-levers; means for moving said connected members into and out of operative relation with said type-sets; and means for supporting a work-sheet in position such that it may be typed upon by any one of said type-sets.

5. In a typewriter of the class described, a suitable frame; a guide carried by said frame; a set of key-levers supported by said frame; a bar movable along and guided in its movements by said guide; a plurality of type-sets carried by and detachably secured to said bar and each of which comprises a plurality of pivotally supported type-bars and means for operating same; means for locking said bar in positions such that each one of the said type-sets will print at one and the same point; a plurality of connecting members pivotally connected one with each of said key-levers; means for moving the free ends of said connecting members into and out of operative relation with the means for operating the type-bars of the particular one of said type-sets selected for use; and means for supporting a work-sheet in position such that it may be typed upon by any one of said type-sets.

6. In a typewriting machine, in combination, a set of keys, actuating members operable by said keys, a type-set comprising type-bars having types thereon corresponding to said keys, supporting means for said type-set permitting movement thereof into and out of effective position with respect to said actuating members, and means for connecting said actuating members and disconnecting them from the type-set while the latter is in effective position.

7. In a typewriter of the class described, a suitable frame; a set of key-levers supported by said frame; a supporting member carried by said frame and movable with respect thereto; a type-set carried by and detachably secured to said supporting member, and which type-set comprises a plurality of pivotally supported type-bars and means for operating the same; means whereby said key-levers may be operatively connected with and disconnected from said

type-set, while the same is held in effective position to print; and means for supporting a work-sheet in position such that it may be typed upon by said type-set.

5. 8. In a typewriter of the class described; a suitable frame; a set of key-levers supported by said frame; a supporting member slidably carried by said frame; a type-set carried by and detachably secured to said supporting member, said type-set being movable therewith to and from a position to coöperate with said key-levers, and which type-set comprises a plurality of pivotally supported type-bars and a plurality 15 of pivotally supported levers operatively connected one with each of said type-bars; a plurality of connecting members pivotally connected one with each of said key-levers; means for moving the free ends of 20 said connecting members into and out of operative engagement with the operating levers for said type-bars, while the type-set is in effective position; and means for supporting a work-sheet in position such that it may be typed upon by said type-set.
9. In a typewriting machine, in combination, a single set of keys, key-levers on which said keys are mounted, a frame in which said key-levers are mounted, two 30 type-sets, a carrier on which said type-sets are detachably mounted, and guiding and controlling means for said carrier permitting the same to be moved to positions so as to bring either type-set into position to co- 35 operate with said key-levers, or to be moved still farther to one side to carry a type-set outside said frame to enable it to be detached from said carrier.
10. In a typewriting machine, in combination, a single set of keys, key-levers on which said keys are mounted, two type-sets, a carrier on which said type-sets are mounted, said carrier being moveable transversely of 40 said key-levers to bring either of said type-sets into effective position to coöperate with said key-levers, means for locking said carrier with either one of said type-sets in effective position, means to connect said key-levers with either type-set when the latter is 45 in effective position, a finger-piece, and means controlled by said finger-piece whereby said locking means and said connecting means may be made effective or ineffective concomitantly.
- 50 55. 11. In a typewriter of the class described, a suitable frame; a set of key-levers supported by said frame; a supporting member carried by said frame; a type-set carried by and detachably secured to said supporting 60 member and comprising a plurality of pivotally supported type-bars, and a plurality of pivotally supported levers operatively connected one with each of said type-bars, and each of which levers is provided with a 65 slot; a plurality of connecting members piv-

otally connected one with each of said key-levers and each of which is provided with a pin at its free end; means for moving said connecting members to thereby cause said pins to move into and out of the slots aforesaid in the operating levers for said type-bars; and means for supporting a work-sheet in position such that it may be typed upon by said type-set.

12. In a typewriter of the class described, a suitable frame; a set of key-levers supported by said frame; a supporting member carried by said frame; type-sets carried by and detachably secured to said supporting member and each comprising a plurality of pivotally supported type-bars, and a plurality of pivotally supported levers operatively connected one with each of said type-bars and each of which levers is provided with a slot; a plurality of connecting members pivotally connected one with each of said key-levers, and each of which is provided with a slot and with a pin at its free end; a movable bail lying within the slots of said connecting members whereby the pins at the free ends thereof may be moved simultaneously into and out of operative engagement with the slots aforesaid in the operating levers for the said type-bars; and means for supporting a work-sheet in position such that it may be typed upon by any one of said type-sets.

13. In a typewriter of the class described, a suitable frame; a set of key-levers supported by said frame; a supporting member carried by said frame; type-sets carried by and detachably secured to said supporting member, and each comprising a plurality of pivotally supported type-bars, and a plurality of pivotally supported levers operatively connected one with each of said type-bars and each of which levers is provided with a slot; a plurality of connecting members pivotally connected one with each of said key-levers, and each of which is provided with a vertically extending slot, and with a pin at its free end; a movable bail lying within the slots of said connecting members whereby the pins at the free ends thereof may be simultaneously moved into and out of operative engagement with the slots aforesaid in the operating levers for said type-bars; two pivotally supported arms whereby said bail is supported; means for operating said arms to thereby swing said bail; and means for supporting a work-sheet in position such that it may be typed upon by any one of said type-sets.

14. In a typewriter of the class described, a suitable frame; a set of key-levers supported by said frame; a supporting member carried by and movable relatively to said frame; a plurality of printing devices carried by said supporting member; means for locking said supporting member in positions

- such that each one of said printing devices will print at one and the same point; a plurality of connecting members pivotally connected one with each of said key-levers; 5 means for moving the free ends of said connecting members into and out of operative relation with the particular one of said printing devices selected for use and for simultaneously operating said locking means 10 to thereby lock and release said supporting member; and means for supporting a work-sheet in position such that it may be typed upon by any one of said printing devices.
15. In a typewriter of the class described, a suitable frame; a guide carried by said frame; a set of key-levers supported by said frame; a bar movable along and guided in its movements by said guide; a plurality of type-sets carried by said bar; a locking pawl 20 for locking said bar in positions such that each one of said type-sets will print at one and the same point; a plurality of connecting members pivotally connected one with each of said key-levers; means for moving 25 the free ends of said connecting members into and out of operative relation with the particular one of said type-sets selected for use and for simultaneously operating said locking pawl to thereby lock and release said 30 bar; and means for supporting a work-sheet in position such that it may be typed upon by any one of said type-sets.
16. In a typewriter of the class described, a suitable frame; a guide carried by said frame; a set of key-levers supported by said frame; a bar movable along and guided in its movements by said guide; a plurality of type-sets carried by and detachably secured 35 to said bar and each of which comprises a plurality of pivotally supported type-bars, and means for operating same; a swinging locking-pawl adapted to enter grooves formed in said bar to thereby lock the same in positions such that each one of said type-sets will print at one and the same point; a 40 plurality of connecting members pivotally connected one with each of said key-levers; means for moving the free ends of said connecting members into and out of operative engagement with the means for operating 45 the type-bars of the particular one of said type-sets selected for use and for simultaneously moving the free end of said swinging pawl into and out of one of said 50 grooves to thereby lock and release said bar; and means for supporting a work-sheet in position such that it may be typed upon by any one of the said type-sets.
17. In a typewriter of the class described, 55 a suitable frame; a set of key-levers supported by said frame; a supporting member carried by and movable relatively to said frame; a plurality of type-sets carried by said supporting member and each of which comprises a plurality of pivotally 60 supported type-bars and a plurality of pivotally supported operating members operatively connected one with each of said type-bars; means for locking said supporting member in positions such that each one of 65 said type-sets will print at one and the same point; a plurality of connecting members pivotally connected one with each of said key-levers and each of which connecting members is provided with a slot; a movable 70 bail lying within the slots of said connecting members whereby the free ends thereof may be moved into and out of operative engagement with the operating members for the type-bars of the particular one of said 75 type-sets selected for use; and means for supporting a work-sheet in such a position that it may be typed upon by any one of said type-sets.
18. In a typewriter of the class described, 80 a suitable frame; a set of key-levers supported by said frame; a supporting member carried by and movable relatively to said frame; a plurality of type-sets carried by said supporting member and each of which 85 comprises a plurality of pivotally supported type-bars, and a plurality of pivotally supported operating members operatively connected one with each of said type-bars; means whereby each separate type-set 90 may be detached from said supporting member independently of the other type-sets; means for locking said supporting member in positions such that each one of 95 said type-sets will print at one and the same point; a plurality of connecting members pivotally connected one with each of said key-levers, and each of which connecting members is provided with a slot; a movable bail lying within the slots of said connecting members whereby the free ends thereof 100 may be moved into and out of operative engagement with the operating members for the type-bars of the particular one of said type-sets selected for use; means for simultaneously moving said bail and for operating said locking means; and means for supporting a work-sheet in position such that it may be typed upon by any one of 105 said type-sets.
19. In a typewriter of the class described, 110 a suitable frame; a set of key-levers supported by said frame; a guide carried by said frame; a bar movable along and guided in its movements by said guide; a 115 plurality of type-sets carried by and detachably secured to said bar, and each of which comprises a plurality of pivotally supported type-bars, and a plurality of pivotally supported operating members operatively connected one with each of said type-bars; two grooves formed in said bar and spaced apart from one another; a pivotally supported locking pawl, the free end of 120 which is adapted to enter one or the other 125

of said grooves to thereby lock said bar in positions such that each one of said type-sets will print at one and the same point; a plurality of connecting members pivotally connected one with each of said key-levers, and each of which connecting members is provided with a vertically extending slot; a movable bail lying within the slots of said connecting members whereby the free ends thereof may be moved into and out of operative engagement with the operating members for the type-bars of the particular one of said type-sets selected for use; means for simultaneously moving said bail and for operating said locking pawl; and means for supporting a work-sheet in position such that it may be typed upon by any one of the said type-sets.

20. In a typewriter of the class described, a suitable frame; a guide carried by said frame; a bar movable along and guided in its movements by said guide; a plurality of printing devices carried by and detachably secured to said bar; a plurality of stops carried by said bar; a movable member located in the path of movement of said stops to thereby limit the movement of said bar; means for moving said movable member out of the path of said stops to thereby permit a further movement of said bar; a set of key-levers supported by said frame; means whereby said set of key-levers may be operatively connected with and disconnected from the particular one of said printing devices selected for use; means to coöperate with said movable member for locking said bar in positions such that each one of said printing devices will print at one and the same point; and means for supporting a work-sheet in position such that it may be typed upon by any one of said printing devices.

21. In a typewriter of the class described, a suitable frame; a guide carried by said frame; a bar movable and guided in its movements by said guide and having a rib extending longitudinally thereof, and the middle portion of which is of less height than the end portions; grooves formed in said rib and located at each end of the middle portion thereof; a plurality of printing devices carried by and detachably secured to said bar; a movable locking pawl adapted to enter the grooves aforesaid to thereby lock said bar in positions such that each one of said printing devices will print at one and the same point; means for moving said locking pawl out of said grooves and to an extent such that it will clear the outer end portions of said rib; a set of key-levers supported by said frame; and means for supporting a work-sheet in position such that it may be typed upon by any one of said printing devices.

22. In a typewriter of the class described,

a suitable frame; a supporting member carried by and movable relatively to said frame; a plurality of printing devices carried by and detachably secured to said supporting member; a plurality of stops carried by said supporting member; a movable member located in the path of movement of said stops and adapted to limit the movement of said movable member; means for moving said movable member out of the path of movement of said stops to thereby permit a further movement of said movable member; a set of key-levers supported by said frame; means whereby said key-levers may be operatively connected with and disconnected from said printing devices; means to coöperate with said movable member for locking said supporting member in positions such that each one of said printing devices will print at one and the same point; means for simultaneously operating said movable member and the means for connecting said key-levers with said printing devices; and means for supporting a work-sheet in position such that it may be typed upon by any one of said printing devices.

23. In a typewriter of the class described, a unitary printing device having a plurality of pivotally supported type-bars; a supporting member to which said printing device may be detachably secured; a set of key-levers; a plurality of connecting members connected one with each of said key-levers and whereby said key-levers may be operatively connected with and disconnected from said printing device; means whereby said connecting members may be simultaneously connected with and disconnected from said printing device; means for supporting a work-sheet in position such that it may be typed upon by said printing device; and a suitable frame whereby said several groups of elements are supported in proper relation with one another.

24. In a typewriting machine, in combination, a set of key-levers, a type-set mounted for movement to and from a position to coöperate with said key-levers, a lock for holding said type-set in position to coöperate with said key-levers, means for connecting said key-levers with said type-set when the latter is in position to coöperate with the former, and means for rendering said lock and said connecting means effective and ineffective concomitantly.

25. In a typewriter of the class described, a unitary type-set comprising a type-bar supporting segment, a plurality of type-bars carried by and pivotally connected with said segment, and a plurality of pivotally supported operating members operatively connected one with each of said type-bars, and each of which members is provided with a slot; a supporting member to which said type-set may be detachably se-

cured; a set of key-levers; a plurality of connecting members pivotally connected one with each of said key-levers and each of which is provided with a slot, and with a 5 pin at its free end; a movable bail lying within the slots of said connecting members and whereby said members may be simultaneously swung about their pivotal connections to thereby move the pins at the 10 ends thereof into and out of the slots aforesaid in the operating members of said type-set; means for supporting a work-sheet in position such that it may be typed upon by said type-set; and a frame whereby said 15 several sets of elements are supported in proper relation with one another.

26. In a typewriter of the class described, a unitary type-set comprising an upper type-bar supporting segment; a plurality 20 of type-bars carried by and pivotally connected with said segment; two depending side members; a bar connecting the lower ends of said side members; a plurality of pivotally supported operating members 25 carried by said bar and operatively connected one with each of said type-bars, and which members are provided each with means whereby they may be operated to thereby operate the type-bars associated 30 therewith; and means carried by said side members whereby said type-set may be detachably secured to a suitable supporting member.

27. In a typewriter of the class described, 35 a unitary type-set comprising an upper type-bar supporting segment; a plurality of type-bars carried by and pivotally connected with said segment; two depending side members; a bar connecting the lower 40 ends of said side members; a plurality of pivotally supported operating members carried by said bar and operatively connected one with each of said type-bars, and each of which members is provided with 45 means whereby they may be operated to thereby operate the type-bars associated therewith; pins carried by said side members and adapted to enter slots provided in a supporting member whereby said type-set 50 may be secured to said supporting member; and a locking member for locking said type-set to said supporting member.

28. In a typewriter of the class described, 55 a supporting member having two brackets spaced apart from one another; a printing device supported by said brackets and detachable therefrom; a set of key-levers; means for simultaneously operatively connecting said key-levers with and disconnecting them from said printing device; 60 means for supporting a work-sheet in a position such that it may be typed upon by said printing device; and a suitable frame for supporting said several sets of elements in proper relation with one another.

29. In a typewriter of the class described, a supporting member having two brackets spaced apart from one another and each of which is provided with two slots; a printing device having pins adapted to enter 70 said slots whereby said printing device is detachably secured to said supporting member; locking means for holding said printing device in place relatively to said brackets; a plurality of key-levers; means 75 whereby said key-levers may be simultaneously operatively connected with and disconnected from said printing device; means for supporting a work-sheet in position such that it may be typed upon by said printing 80 device; and a suitable frame for supporting said several elements in proper relation with one another.

30. In a typewriter of the class described, 85 a suitable frame; a set of key-levers supported by said frame; a supporting member carried by said frame; a type-set carried by and detachably secured to said supporting member and having a plurality of pivotally supported type-bars; means whereby said 90 set of key-levers may be operatively connected with and disconnected from said type-bars; a ribbon-vibrating member carried by said type-set; an operating member supported from the frame of the machine, 95 and the free end of which is in operative engagement with said ribbon-vibrating member, but which free end is disconnectible from said member so that the same may be moved out of engagement with said free 100 end; and means whereby said ribbon-vibrating member is operated from said type-set.

31. In a typewriter of the class described, 105 a suitable frame; a set of key-levers supported by said frame; a supporting member carried by said frame; a type-set carried by and detachably secured to said supporting member and having a plurality of pivotally supported type-bars; means whereby said set 110 of key-levers may be operatively connected with and disconnected from said type-bars; a universal bar carried by said type-set; a reciprocating intermediate member supported from the frame of the machine and 115 adapted to be engaged and operated by said universal bar; a bell-crank lever with one arm of which said reciprocating member is operatively connected, and the other arm of which extends toward and the free end of 120 which lies adjacent said type-set; a ribbon-vibrating member carried by said type-set; and means whereby the free end of the last-mentioned arm of said bell-crank lever may be detachably engaged with said ribbon- 125 vibrating member.

32. In a typewriter of the class described, 130 a suitable frame; a set of key-levers supported by said frame; a supporting member carried by said frame; a type-set carried by

and detachably secured to said supporting member and having a plurality of pivotally supported type-bars; means whereby said set of key-levers may be operatively connected with and disconnected from said type-bars; a universal bar carried by said type-set; a reciprocating intermediate member supported from the frame of the machine and adapted to be engaged and operated by said universal bar, and which member is provided with a vertically-extending slot; a vertically shiftable bell-crank lever, one arm of which is in engagement with said slot, and the other arm of which extends toward and the free end of which lies adjacent said type-set; a vertically shiftable ribbon-vibrating member carried by said type-set; and means whereby the free end of the last-mentioned arm of said bell-crank lever may be detachably engaged with said ribbon-vibrating member.

33. In a typewriter of the class described, a suitable frame; a set of key-levers supported by said frame; a supporting member carried by said frame; a type-set carried by and detachably secured to said supporting member, and which type-set comprises a plurality of pivotally supported type-bars and means for operating the same; means whereby said key-levers may be operatively connected with and disconnected from said type-set; a universal bar carried by said type-set; and an escapement mechanism operated from said universal bar.

34. In a typewriter of the class described, a suitable frame; a set of key-levers supported by said frame; a supporting member carried by said frame; a type-set carried by and detachably secured to said supporting member, and which type-set comprises a plurality of pivotally supported type-bars, and a plurality of pivotally supported levers operatively connected one with each of said type-bars; a plurality of connecting members pivotally connected one with each of said key-levers; means for moving the free ends of said connecting members into and out of operative engagement with the operating levers of said type-bars; a universal bar carried by said type-set; a reciprocating intermediate member supported from the frame of the machine and operated by said universal bar; and an escapement mechanism operated by said intermediate member.

35. In a typewriter of the class described, a suitable frame; a set of key-levers supported by said frame; a supporting member carried by said frame; a printing device carried by and detachably secured to said supporting member; a plurality of connecting members pivotally connected one with each of said key-levers; means for moving the free ends of said connecting members into and out of operative relation with said

printing device; a ribbon-vibrating member carried by said printing device; an operating member supported from the frame of the machine and the free end of which is in operative engagement with said ribbon-vibrating member, but which free end is disconnectible from said member, so that the same may be moved out of engagement with said free end; and means whereby said ribbon-vibrating member is operated from said printing device.

36. In a typewriter of the class described, a suitable frame; a set of key-levers supported by said frame; a supporting member carried by said frame; a printing device carried by and detachably secured to said supporting member; a plurality of connecting members pivotally connected one with each of said key-levers; and means for moving the free ends of said connecting members into and out of operative relation with said printing device, when the latter is in position to coöperate therewith.

37. In a typewriter of the class described, a suitable frame; a set of key-levers supported by said frame; a supporting member carried by said frame; a type-set carried by and detachably secured to said supporting member and comprising a plurality of pivotally supported type-bars, and a plurality of pivotally supported levers operatively connected one with each of said type-bars and each of which levers is provided with a slot; a plurality of connecting members pivotally connected one with each of said key-levers and each of which is provided with a pin at its free end; means for moving said connecting members to thereby cause said pins to move into and out of the slots aforesaid in the operating levers for said type-bars; a ribbon-vibrating member carried by said type-set; an operating member supported from the frame of the machine and the free end of which is in operative engagement with said ribbon-vibrating member, but which free end is disconnectible from said member so that the same may be moved out of engagement with said free end; and means whereby said ribbon-vibrating member is operated from said type-set.

38. In a typewriter of the class described, a suitable frame; a set of key-levers supported by said frame; a supporting member carried by said frame; a type-set carried by and detachably secured to said supporting member and comprising a plurality of pivotally supported type-bars, and a plurality of pivotally supported levers operatively connected one with each of said type-bars and each of which levers is provided with a slot; a plurality of connecting members pivotally connected one with each of said key-levers, and each of which is provided with a slot, and with a pin at its free end; a movable bail lying within the slots of said

- connecting members whereby the pins at the free ends thereof may be moved simultaneously into and out of operative engagement with the slots aforesaid in the operating 5 levers for said type-bars; a universal bar carried by said type-set; a reciprocating intermediate member supported from the frame of the machine and adapted to be engaged and operated by said universal bar; 10 a bell-crank lever with one arm of which said reciprocating member is operatively connected, and the other arm of which extends toward and the free end of which lies adjacent said type-set; a ribbon-vibrating 15 member carried by said type-set; and means whereby the free end of the last-mentioned arm of said bell-crank lever may be detachably engaged with said ribbon-vibrating member. 20 39. In a typewriter of the class described, a suitable frame; a set of key-levers supported by said frame; a supporting member carried by said frame; a type-set carried by and detachably secured to said supporting 25 member and comprising a plurality of pivotally supported type-bars, and a plurality of pivotally supported levers operatively connected one with each of said type-bars and each of which is 30 provided with a slot; a plurality of connecting members pivotally connected one with each of said key-levers, and each of which is provided with a vertically-extending slot, and with a pin at its free end; a 35 movable bail lying within the slots of said connecting members whereby the pins at the free ends thereof may be simultaneously moved into and out of operative engagement with the slots aforesaid in the operating 40 levers for said type-bars; two pivotally supported arms whereby said bail is supported; means for operating said arms to thereby swing said bail; a universal bar carried by said type-set; a reciprocating intermediate 45 member supported from the frame of the machine and adapted to be engaged and operated by said universal bar, and which member is provided with a vertically-extending slot; a vertically shiftable bell-crank 50 lever, one arm of which is in engagement with said slot, and the other arm of which extends toward and the free end of which lies adjacent said type-set; a vertically shiftable ribbon-vibrating member carried by 55 said type-set; and means whereby the free end of the last-mentioned arm of said bell-crank lever may be detachably engaged with said ribbon-vibrating member. 60 40. In a typewriter of the class described, a suitable frame; a set of key-levers supported by said frame; a supporting member carried by and movable relatively to said frame; a plurality of printing devices carried by and detachably secured to said supporting member; means for locking said 65
- supporting member in positions such that each one of said printing devices will print at one and the same point; means whereby said set of key-levers may be operatively connected with and disconnected from the particular one of said printing devices selected for use, while the selected printing device is in position to coöperate with said key-levers; a traveling platen for supporting a work-sheet in position such that it may be typed upon by any one of said printing devices; a single escapement mechanism; and means whereby said escapement mechanism may be operated by any one of said printing devices. 70 75 80 85 90 95 100 105 110 115 120 125 130
41. In a typewriter of the class described, a suitable frame; a set of key-levers supported by said frame; a supporting member carried by and movable relatively to said frame; a plurality of printing devices carried by and detachably secured to said supporting member; means for locking said supporting member in positions such that each one of said printing devices will print at one and the same point; means whereby said set of key-levers may be operatively connected with and disconnected from the particular one of said printing devices selected for use; a plurality of ribbon-vibrating members associated one with each of said printing devices; a plurality of levers operatively connected one with each of said vibrating members; a rod whereby said levers are supported and along which they are movable; a guide carried by each of said printing devices and adapted to guide said levers; and means whereby said levers are operated from the particular printing device in use at a given time. 100
42. In a typewriter of the class described, a suitable frame; a set of key-levers supported by said frame; a supporting member carried by and movable relatively to said frame; a plurality of printing devices carried by and detachably secured to said supporting member; means for locking said supporting member in positions such that each one of said printing devices will print at one and the same point; a plurality of vertically movable ribbon-vibrating members carried one by each of said printing devices; a plurality of bell-crank levers, one arm of each of which is slotted at its free end, and which free ends are adapted to detachably engage said ribbon-vibrating members; a rod whereby said levers are supported and along which they are movable; a plurality of guides carried one by each of said printing devices and whereby the arms aforesaid of said bell-crank levers are guided; a reciprocating member adapted to be operated by the particular one of said printing devices in use at a given time; and means whereby movement is transmitted from said reciprocating member to the bell- 130

crank lever associated with the particular printing device in use through the second arm of said lever.

43. In a typewriter of the class described,

- 5 a suitable frame; a set of key-levers supported by said frame; a supporting member carried by and movable relatively to said frame; a plurality of type-sets carried by said supporting member and each of
- 10 which comprises a plurality of pivotally supported type-bars; means for locking said supporting member in positions such that each one of said type-sets will print at one and the same point; a plurality of connect-
- 15 ing members pivotally connected one with each of said key-levers; means for moving the free ends of said connecting members into and out of operative relation with the particular one of said type-sets selected
- 20 for use; a traveling platen for supporting a work-sheet in position such that it may be typed upon by any one of said type-sets; a universal bar associated with each of said type-sets; a single escapement mechanism;
- 25 and means whereby said escapement mechanism may be operated by the universal bar of the particular type-set in use at a given time.

44. In a typewriter of the class described,

- 30 a suitable frame; a set of key-levers supported by said frame; a supporting member carried by and movable relatively to said frame; a plurality of type-sets carried by said supporting member and each of which
- 35 comprises a plurality of pivotally supported type-bars; means for locking said supporting member in positions such that each one of said type-sets will print at one and the same point; a plurality of connect-
- 40 ing members pivotally connected one with each of said key-levers; means for moving the free ends of said connecting members into and out of operative relation with the particular one of said type-sets selected for
- 45 use; a universal bar carried by each of said type-sets; a plurality of ribbon-vibrating members associated one with each of said type-sets; a plurality of levers operatively connected one with each of said vibrating
- 50 members; a rod whereby said levers are supported and along which they are movable; a guide carried by each of said type-sets and which guides are adapted to guide said levers; and means whereby said levers are operated by the universal bar of the particular one of said type-sets in use at a given time.

45. In a typewriter of the class described, a suitable frame; a set of key-levers sup-

- 60 ported by said frame; a supporting member carried by and movable relatively to said frame; a plurality of type-sets carried by said supporting member, and each of which comprises a plurality of pivotally sup-
- 65 ported type-bars; means for locking said

supporting member in positions such that each one of said type-sets will print at one and the same point; a plurality of connecting members pivotally connected one with each of said key-levers; means for moving the free ends of said connecting members into and out of operative relation with the particular one of said type-sets selected for use; a plurality of vertically movable ribbon-vibrating members carried

70

one by each of said type-sets; a plurality of bell-crank levers, one arm of each of which is slotted at its free end, and which free ends are adapted to detachably engage said ribbon-vibrating members; a rod whereby said levers are supported and along which they are movable; a plurality of guides carried one by each of said type-sets and whereby the arms aforesaid of said bell-crank levers are guided; a reciprocating member adapted to be operated from the particular one of said type-sets in use at a given time; and means whereby movement is transmitted from said reciprocating member to the bell-crank lever associated with the particular type-set in use through the second arm of said lever.

46. In a typewriter of the class described:

a suitable frame, a guide carried by said frame; a set of key-levers supported by said frame; a bar movable along and guided in its movements by said guide; a plurality of type-sets carried by and detachably secured to said bar; means for locking said bar in positions such that each one of said type-sets will print at one and the same point; means whereby said set of key-levers may be operatively connected with and disconnected from the particular one of said type-sets selected for use, while the selected type-set is in position to coöperate with said key levers, a traveling platen for supporting a work-sheet in position such that it may be typed upon by any one of said type-sets; a single escapement mechanism; and means whereby said escapement mechanism may be operated by any one of said type-sets.

95

47. In a typewriter of the class described,

a suitable frame; a guide carried by said frame; a set of key-levers supported by said frame; a bar movable along and guided in its movements by said guide; a plurality of type-sets carried by and detachably secured to said bar; means for locking said bar in positions such that each one of said type-sets will print at one and the same point; means whereby said set of key-levers may be operatively connected with and disconnected from the particular one of said type-sets selected for use, while the selected type-set is in position to coöperate with said key levers; a plurality of ribbon-vibrating members associated one with each of said type-sets; a plurality of levers operatively connected one with each of said vibrating mem-

bers; a rod whereby said levers are supported and along which they are movable; a guide carried by each of said type-sets and adapted to guide said levers; and means 5 whereby said levers are operated from the particular type-set in use at a given time.

48. In a typewriter of the class described, a suitable frame; a guide carried by said frame; a set of key-levers supported by said frame; a bar movable along and guided in its movements by said guide; a plurality of type-sets carried by and detachably secured to said bar; means for locking said bar in positions such that each one of said 10 type-sets will print at one and the same point; means whereby said set of key-levers may be operatively connected with and disconnected from the particular one of said type-sets selected for use; a plurality of 15 vertically movable ribbon-vibrating members carried one by each of said type-sets; a plurality of bell-crank levers, one arm of each of which is slotted at its free end, and which free ends are adapted to detachably 20 engage said ribbon-vibrating members; a rod whereby said levers are supported and along which they are movable; a plurality of guides carried one by each of said type-sets and whereby the arms aforesaid of said 25 30 bell-crank levers are guided; a reciprocating member adapted to be operated by the particular one of said type-sets in use at a given time; and means whereby movement is transmitted from said reciprocating member to the bell-crank lever associated 35 with the particular type-set in use through the second arm of said lever.

49. In a typewriter of the class described, a suitable frame; a guide carried by said frame; a set of key-levers supported by said frame; a bar movable along and guided in its movements by said guide; a plurality of type-sets carried by and detachably secured to said bar; means for locking said bar in 40 positions such that each one of said type-sets will print at one and the same point; means whereby said set of key-levers may be operatively connected with and disconnected from the particular one of said type-sets 45 selected for use, while the selected type-set is in position to coöperate with said key-levers; a traveling platen for supporting a work-sheet in position such that it may be typed upon by any one of said type-sets; a 50 universal bar associated with each of said type-sets; a single escapement mechanism; and means whereby said escapement mechanism will be operated by the universal bar of the particular type-set in use at a given 55 time.

50. In a typewriter of the class described, a suitable frame; a guide carried by said frame; a set of key-levers supported by said frame; a bar movable along and guided in 60 its movements by said guide; a plurality of

type-sets carried by and detachably secured to said bar; means for locking said bar in positions such that each one of said type-sets will print at one and the same point; means whereby said set of key-levers may be 70 operatively connected with and disconnected from the particular one of said type-sets selected for use, while the selected type-set is in position to coöperate with said key-levers; a universal bar carried by each of 75 said type-sets; a plurality of ribbon-vibrating members associated one with each of said type-sets; a plurality of levers operatively connected one with each of said vibrating members; a rod whereby said levers 80 are supported and along which they are movable; a guide carried by each of said type-sets, and which guides are adapted to guide said levers; and means whereby said levers are operated by the universal bar of 85 the particular one of said type-sets in use at a given time.

51. In a typewriter of the class described, a suitable frame; a guide carried by said frame; a set of key-levers supported by said frame; a bar movable along and guided in its movements by said guide; a plurality of type-sets carried by and detachably secured to said bar; means for locking said bar in 90 positions such that each one of said type-sets will print at one and the same point; means whereby said set of key-levers may be operatively connected with and disconnected from the particular one of said type-sets selected for use; a plurality of vertically 95 movable ribbon-vibrating members carried one by each of said type-sets; a plurality of bell-crank levers, one arm of each of which is slotted at its free end, and which free ends are adapted to detachably engage said ribbon-vibrating members; a rod whereby said 100 levers are supported and along which they are movable; a plurality of guides carried one by each of said type-sets, and whereby the arms aforesaid of said bell-crank levers 105 are guided; a reciprocating member having an arm provided with a slot into which pins carried by the other arms of said bell-crank levers may be moved; and a plurality of universal bars, one carried by each of said type-sets, and each of which universal bars is adapted to engage with and transmit motion to said reciprocating member.

52. In a typewriting machine, the combination with a platen, of a plurality of type-sets, each type-set comprising type-bars, a single set of key-levers, a plurality of sets of operating levers, one set of the latter for each set of type-bars, a single set of intermediate members, means for effecting a relative movement between said type-sets and said key-levers, and means for moving said intermediate members to connect or disconnect said key-levers with either set of operating levers.

53. In a typewriting machine, the combination with a platen, of a plurality of type-sets, each type-set comprising type-bars, a single set of key-levers, a plurality of sets of operating levers, one set of the latter for each set of type-bars, means to move either type-set into co-operative relation with said key-levers, a single set of links pivotally connected to said key-levers, and a universal member engaging with all of said links to connect or disconnect said key-levers with either set of operating levers.

54. In a typewriting machine, the combination with a platen, of a plurality of type-sets, each type-set comprising type-bar supports for type-bars, one for each type-set, a plurality of ribbon-vibrating members, one for each type-set, one of said ribbon-vibrat-

ing members being carried by each type-bar support, a plurality of ribbon-vibrating levers, one for each ribbon-vibrating member, an actuating element having an engaging portion for said ribbon-vibrating levers, said type-bar supports being detachably mounted, said ribbon-vibrating members being detachably connectible with said ribbon-vibrating levers, and means to prevent said ribbon-vibrating levers from dropping out of alinement with the engaging portion of said actuating element when the connections between said ribbon-vibrating members and said ribbon-vibrating levers are broken.

JOHN WALDHEIM.
